SCOURING DEVICE

Joseph R. Crockford, Chicago, Ill., assignor to
Efficiency Specialties, Omaha, Nebr., a corpora-
tion of Nebraska

Application July 5, 1940, Serial No. 343,979

2 Claims. (Cl. 15—209)

This invention relates to scouring devices, and particularly those of the character employed for cleansing and scouring pots, pans and other household implements, although the device is also capable of many other uses.

One of the objects of the invention is to provide an all-metal scouring device of simple and effective construction, the device, including the scouring or abrasive material forming a part of it, being preferably composed of non-corrosive metal so that it is capable of long life and will not stain or discolor the articles being cleansed. A further object of the invention is to provide a metal holder for a mass of scouring material and to provide a novel means of attaching or fastening the scouring material securely to said holder so that it cannot be dislodged therefrom during normal scouring operations, such attaching means being preferably so-called "surface" or spot-welding.

Another object of the invention is to provide an improved method of assembling the scouring device, said method involving the step of welding a tangled mass of abrasive material, such as helical or coiled metallic ribbon or strands to at least one face of a metallic plate, forming a manipulating handle for the device.

More particularly, the invention contemplates the provision of a sheet metal plate of non-corrosive metal, arched or curved to fit the fingers, and having secured to its under or bottom face adjacent one end, a mass of the tangled helical or coiled elastic ribbon or strand, portions of the mass extending beyond and protecting the edges of the plate.

Scouring devices of the character of that herein described may be classified in two general groups, namely, those in which a wad, pad or mass of fibrous metallic wool or strands is held in direct contact with the hand of the user and applied to the surface of the article to be scoured, and those in which the scouring material, also of metallic wool, strands, shavings or curls are held in a wad or mass and such wad or mass is fastened, detachably or permanently in some sort of a holder which is held in the hand during the scouring operation.

One of the objections to scouring devices comprised in the first group is that the fingers of the user contact directly with the scouring material, and since such material, and particularly after some use, often breaks up into fine particles, there is the likelihood that such particles can penetrate the skin of the fingers and cause infection. Moreover, since the scouring material

is held in the hand, there is a necessity for the use of more scouring material than is actually necessary since the entire pad is not actually consumed but a considerable portion of the pad must be discarded as soon as the pad becomes reduced in size after use so that it cannot be conveniently held and applied to the article or surface to be scoured.

An objection encountered in the scouring devices in the second group is that the holders in which the wads or pads of scouring material have been disposed do not always firmly hold the scouring material and are so shaped that they cannot be properly held with a natural grip to enable a maximum of pressure to be applied by the fingers with a minimum of effort on the part of the user.

The present invention therefore contemplates the provision of a scouring device in which a minimum of amount of scouring material is used; in which a simple yet highly effective method of attaching the scouring material to a holder or handle is utilized, and in which a shaped handle of novel contour, fitting the fingers and affording protection for the finger nails is provided by which the hand holds the handle in a natural and normal pressure-applying position whereby a great amount of scouring work can be performed with a minimum of effort and without tiring the user of the device.

Another deficiency often met in present-day scouring devices of the kind in which the scouring material is held in a handle, is the inability of the device to provide adequate drainage. Accordingly, in many of the known scouring devices, grease, discolored water, food particles and the like accumulate in the mass of scouring material which soon becomes odorous, rusty (if ordinary steel wool is employed as the scouring material) and messy, thus requiring it to be discarded after a relatively short time. The present invention contemplates the provision of a scouring device which can be hung up or suspended on a hook or nail to thereby greatly facilitate drainage from the scouring material, and which by reason of the relatively small amount of scouring material employed and its relationship to the handle portion to which it is preferably permanently attached, will not readily harbor or collect food particles, dirty water, grease and scrapings and will accordingly remain clean and sanitary for its entire useful life.

In the accompanying drawing, forming a part hereof, Fig. 1 is a plan view of a scouring device constructed in accordance with the invention;

Fig. 2 is a perspective view showing how the device is held when in use; Fig. 3 is a sectional view on the line 3—3 of Fig. 1, looking in the direction of the arrows; Fig. 4 is a view of the under-side of the device; Fig. 5 is an enlarged view of several of the coiled metallic strands used as the scouring material; Fig. 6 is a plan view of a modified structure; and Fig. 7 is a sectional view on the line 7—7 of Fig. 6, looking in the direction of the arrows.

Referring to the structure shown in Figs. 1 to 5 inclusive, the improved scouring device primarily consists of two main elements, namely, a body portion or handle 1 and a mass of scouring material 2 attached thereto.

The body portion or handle is preferably made of sheet metal of a non-corrosive nature to thereby remain unaffected by the action of water, soaps, grease and acids. For the purpose, stainless steel, Monel metal or some other material is used. If a corrosive metal is employed, it can, if desired, be coated or plated with corrosion-resisting substance.

The body portion or handle 1 is dished in the form shown to thereby present a concave upper face 3 and a convex lower face or bottom 4. The forward or wider end of the handle is curved or rounded as indicated at 5, said curved or rounded end being upturned to thereby provide a finger-protecting flange 6 surrounding the finger depression 7 in which the fingers rest during the scouring operation, as clearly shown in Fig. 2. At a substantially central point, remote from the forward end 5 of the handle, is formed an upwardly and longitudinally extending hump or rib 8 serving to not only add stiffness and rigidity to the handle but to provide on the under side of the handle, a recess 9 for the reception of the thumb of the user.

The formation of the body portion or handle is such that the fingers of the user's hand naturally fall into the proper position when grasping the handle. That is to say, four fingers of the hand conveniently fit into the depression 7 and the finger nails thereon are protected by the flange 6, while the thumb naturally seeks and fits into the recess 9 on the under side of the handle. With the fingers of the user located in the positions described, the device is held naturally and comfortably and a considerable amount of pressure can be applied to the device because of the position of the fingers, with a minimum amount of effort. Since a comfortable and natural grip on the device is afforded and a cramped position of the fingers during the scouring operation is avoided, the scouring operation is greatly facilitated and a more thorough scouring job with less effort is the result.

The scouring material, indicated at 2, preferably but not necessarily, consists of a tangled mass of fibrous material such as a mass of resilient helical coils of metallic ribbon, tape or strands such as shown at 10 in Fig. 5, the method of manufacture of such material providing relatively sharp cutting edges on the ribbon or tape so that it is highly efficient as a scouring means. So-called metallic wool, particularly when composed of non-corrosive metals such as stainless steel, Monel metal or the like, might also be used as scouring material. The helical coils 10 of springy metallic ribbon or tape, tend to interlock or intermingle in a desirable manner to hold them together in a mass.

For attaching the scouring material to the body portion or handle, I utilize spot-welding or

so-called "surface" welding at spaced points which firmly attaches the mass of metallic fibres to the under face or bottom 4 of the handle adjacent the forward end of the same and below

5 the finger depression 7, as clearly shown. The welds, indicated at 11, so securely affix the scouring material to the face of the plate that the scouring material can be frictionally and forcibly applied to the surface of the article to be 10 scoured with a great deal of pressure without the strands or fibres becoming detached from the handle. Moreover, the nature of the material is such that the coils of material interlock or tangle and mass together and overlie the 15 spaced points of weld so that the means of securing of the mass of scouring material to the body portion or handle is substantially invisible and is not apparent except upon very close examination.

20 The mass of scouring material is so disposed on the body portion or handle that it extends beyond the edges of the same. The normal curling tendency of the strands or fibres of such material causes the projecting portion of the scouring material to curl over the edges of the handle as indicated at 12 in Figs. 3 and 7 and thus cover and protect these edges from contact with the article being scoured.

25 To permit the device to be hung up and facilitate the drainage of water therefrom a hole 13 is formed in the handle at the end of the same remote from the scouring material. When the device is suspended on a hook or nail, the accumulated water will drain out of the scouring 30 material together with food particles and other accumulations.

35 While I have shown the scouring material to be attached to a sheet metal handle or body by means of spaced spot welds, other means of attaching the same may be utilized. For example, in Figs. 6 and 7 is shown a plurality of spaced tongues 14 stamped out of the body portion or handle, these tongues being bent over and around parts of the scouring material to thus affix it to the handle. It might also be possible to attach the 40 scouring material to the handle, by staples, wire stitching, rivets or other means, as will be obvious to those skilled in the art.

45 While the handle or body portion of the device is shown in a decidedly convenient form to facilitate the scouring operation, various changes in shape may be made to suit conditions. For example, in Figs. 3 and 7 is shown the rear edge of the handle upturned as indicated at 15 to thereby provide a scraper blade to be used in cooperation with the scouring material and loosen thick or hardened accumulations of grease or other materials on the surface to be scoured, prior to the application of the scouring material 50 to the surface.

55 The improved scouring device has herein been described as being adapted for the scouring of pots, pans and other kitchen utensils, although it will be understood that the device is not limited to such use, since it will be found of value whenever a scouring, scraping or cleansing action is required. It is so shaped that it can be held naturally in the hand; maximum pressure can be applied to the surface being scoured without 60 readily tiring the fingers; drainage of the scouring material is easily had, since it is in a relatively thin layer, rather than in a thick mass or pad as is the case with other scouring devices, and since the device is wholly composed of non-corrosive materials, it will not rust or become dis-

colored in use and thereby have a long, useful life.

What I claim is:

1. A scouring device comprising, a single thickness metal plate forming a handle member, said plate having a wide rounded forward portion provided with a concave upper face and convex under surface, a mass of metallic fibres fused to the convex under surface of the plate at the forward portion of the same, portions of said mass normally curling upward and over the edge of said forward portion to thereby protect the same, the side edges of the plate converging from said rounded forward portion of the plate to the rear end of the plate, the part of said plate located between said converging edges being dished to produce a convex upper surface and concave under surface, said last-mentioned surfaces forming finger-engaging portions on the plate rearwardly of the mass of metallic fibres. 20

2. A scouring device comprising, a single thickness metal plate forming a handle member, said plate having a forward portion provided with a rounded upturned edge, said forward portion being provided with a convex under surface adjacent to and extending rearwardly of said edge, said plate being reversely arched from the inner end of said convex surface to the rear edge of the plate, whereby the under surface of the plate has both convex and concave merging surfaces, a mass of metallic fibres spot welded over the convex under surface of the plate, said fibres terminating substantially at the forward end of the concave under surface, the portion of the plate free of fibres constituting a finger-engaging portion on the plate located rearwardly of the mass of metallic fibres, said finger-engaging portion including a convexly curved surface on its upper face. 15
